DESIGN.

—o—
V. G. SCHUCK.
BRAID.

No. 19,748.

Patented Apr. 1, 1890.

UNITED STATES PATENT OFFICE.

VALENTINE G. SCHUCK, OF NEW YORK, N. Y., ASSIGNOR TO THE SUTRO BROTHERS BRAID COMPANY, OF NEW YORK.

DESIGN FOR BRAID.

SPECIFICATION forming part of Design No. 19,748, dated April 1, 1890.

Application filed February 8, 1890. Serial No. 339,740. Term of patent 7 years.

To all whom it may concern:

Be it known that I, VALENTINE G. SCHUCK, of the city, county, and State of New York, have invented and produced a new and original Design for Braid, of which the following is a full and exact description, reference being had to the accompanying photograph, and to the letters of reference marked thereon, making a part of this specification.

This design relates specially to that class of braid having a wavy or serpentine configuration in the length thereof, and the nature is clearly shown in the accompanying photograph, in which it is shown as produced in different colors upon different pieces of braid.

It consists in a wave braid A, having one of its faces ornamented by a series of separate border-lines *b b b*, produced upon the margin of and embracing each outwardly-curved projection along the edges of the braid in a color contrasting with that of the remainder of the braid, said border-lines being made to follow each curve for a portion only of the length of the curve, so that the several curves are separated from each other by definite in-

tervals *c c c* at the re-entrant portions of the edges of the braid, while the ends of each curved border-line *b* on one edge of the braid are thus made to terminate opposite the middle of one of the corresponding curved border-lines on the opposite edge of the braid, in manner as shown in the photograph thereof.

I claim as my invention—

The design illustrated in the accompanying photograph and described in the specification, and which consists of a wave braid having a surface ornamentation produced by a series of separate marginal lines contrasting in color with the remainder of the braid and each conforming with and following for a portion of its length one of the outward curves defining the edges of the braid.

In testimony whereof I have signed my name to this specification in the presence of two subscribing witnesses.

VALENTINE G. SCHUCK.
